UNITED STATES PATENT OFFICE

PAUL W. ERNSBERGER, OF ADA, OHIO

BAG HOLDER

Application filed May 6, 1931. Serial No. 535,434.

My invention has for its object to provide a means for readily securing a bag in position for the purpose of filling the bag with a material and wherein the securing means may be readily operated to release the bag when the bag has been filled. The invention is particularly adapted for use in connection with material dispensing machines or devices where material is discharged into flexible containers, such as cloth bags. It finds advantageous use in grain elevators where the grain is directed from chutes into bags.

The bag holders embodying my invention are so formed that the bags may be readily placed in position on the end of the chute and closed about the chute, and when the bags have been filled they are readily disconnected from the end of the chute without raising the bags.

The invention may be contained in structures of different forms and, to illustrate a practical application of the invention, I have selected as an example of such structures, a bag holding device particularly adaptable for spouts of different forms for directing material of different kinds into containers that may be supported on the ends of the spouts. The particular construction selected as an example is shown in the accompanying drawings and is described hereinafter.

Fig. 1 of the drawings illustrates a perspective view of the bag holding device and illustrates the chute and the bag connected to the end of the chute by the holding device. Fig. 2 illustrates a perspective view of the holding end of the chute by the holding device. Fig. 3 illustrates a view of a vertical section of the device and a part of the chute. Fig. 4 illustrates a vertical section of the device taken on a plane located at right angles to the plane of the section shown in Fig. 3.

In the particular form of construction shown in the drawings, a chute 1, which is ordinarily supported from the rafters or upper structure of an elevator building, depends to a point in proximity to the floor or to a platform. The empty bags are connected to the chute 1 to receive the grain from the chute. The lower end of the chute 1 is provided with a pair of plates 2 that are secured to opposite

sides of the chute. If the chute 1 has a width less than that of the plates, a suitable block 3 may be secured on one of the sides of the chute to provide a suitable support or foundation for the plates 2. The lower edges of the plates 2 are provided with shells 4, oblong in form, and provided with openings 5. A pair of members 6 may be slidably movable relative to the plates 2. The members 6 are preferably T-shaped and may be referred to as T-bars. The cross parts of the T-bars 6 are located within the shells 4. The T-bars, preferably, substantially fit the interior of the shells 4, or are provided with enlarged ends which fit the end portions of the shells 4 for guiding movements of the cross parts 7 of the T-bars. The shanks 8 of the T-bars or members 6 protrude through the upper walls of the shells 4 and are connected with a means for raising and lowering the T-bars. Bag supporting pointed pins 9 are connected in the ends of the cross member of the T-bar and extend through the openings 5 whereby vertical movements of the members 6 raise and lower the pins 9 and consequently cause the pins 9 to project through the openings 5, or are lowered to locate the pointed ends of the pins 9 within the shells 4.

The T-bars or members 6 are raised and lowered by a pair of cam bars 12. The cam bars 12 are formed of flat metal bars that are connected together by a handle 13 and are supported for sliding movement by the plates 2. The bars 12 are provided with parallel slots 14 and slots 15 that are located intermediate the slots 14. The parallel slots 14 are inclined to the lower edges of the bars 12 and the slots 15 are, preferably, located intermediate the slots 14. Each slot 15, in each bar 12, slopes preferably, from the lower end of one slot 14 to the upper end of the other slot 14. The lower end portions 16 of the slots 14 and the upper end portions 17 of the slots 15 extend parallel to the upper and lower edges of the bars 12 and, hence, the slots 14 and 15 are angular in form.

The bars 12 are connected to the plates 2 by means of pins 18. If desired, suitable washers and cotterpins may be located on the ends of the pins to maintain the bars 12 in position.

and enable them to slide lengthwise across the upper ends of the plates 2. The pins and the slots raise and lower the cam bars 12 to raise and lower the pointed pins 9, the horizontal parts of the slots 14 and 15 lock the T-bars in position and prevent movement when the bags are forced on the pointed pins. When the bars 12 are moved lengthwise they are raised or lowered, depending on the direction of their movement, by reason of the movement of the edges of the slots 14 along the pins 18. The members 6 are connected to the bars 12 and are raised and lowered with the raising and lowering of the bars 12, to raise and lower the pins 9 and to cause them to project from the shells 4 or be receded in the shells 4.

In the particular form of construction shown, the T-bars or members 6 are connected to the bars 12 by means of pins 20 that extend through the slots 15. The upper ends of the T-bars are guided in their vertical movements by links 21 which are pivotally connected to the pins 20 and to one set of the pins 18. The links 21 thus coact with the inner surfaces of the shells 4 to guide the T-bars or members 6 in their reciprocatory movements produced by the sliding movements of the cam bars 12. Since the slots 15 operate on the pins 20 to raise and lower the T-bars, while the bars 12 are raised and lowered by the cam slots 14, the movement of the T-bars or members 6 is equal to the sum of the heights of any one of the slots 14 and the height of any one of the slots 15. This is due to the fact that the bars 12 are raised and lowered when moved longitudinally and, by reason of the slope of the slots 15, the T-bars are moved relative to the bars 12. This affords extended movements of the pins and consequently enables the use of relatively long pins as compared to the width of the bars 12.

When it is desired to fill a bag, the handle 13 is pressed towards the chute which operates to raise the bars 12 by the movement of the edges of the slots 14 along the pins 18 and to raise the members 6 and the pins 9 connected to the members 6 by, not only the raising movement of the bars 12, but also by reason of the slots 15 which move the members upwardly relative to the bars 12. This locates the points of the pins 9 well above the tops of the shells 4. The edge of the open end of the bag is then forced on the pins and at the same time is tightly drawn around the chute. The cloth of the bag is punctured by the pins which hold the bag in position on the end of the chute. The open ends of the bags are invariably much larger than the chute and the extra amount of the bag material at the open end may be folded over and secured to another of the pins. Thus the interior of the bag is completely closed and the escape of dust from the grain is prevented.

When the bag has been placed in position, the chute shutter 23 may be opened and the grain allowed to enter the bag. When the bag has been filled the shutter 23 may be closed. The bag may then be released from the chute by merely pulling the handle 13 outward which lowers the cam bars 12 and, at the same time, further lowers the T-bars or members 6 which move the pointed pins 9 into the shells 4 and allows the bag to drop by the weight of the material in the bag from the end of the chute.

I claim:

1. In a bag holder, a chute, a pair of plates secured to opposite sides of the chute, a pair of connected slideable bars having cam slots and pins extending through one set of the slots for shiftably supporting the bars for horizontal and vertical movements of the bars, a pair of shells connected to the plates, a pair of T-bars supported in the shells and having pointed pins connected to the ends of the cross members of the T-bars and extending through the tops of the shells for engaging the ends of bags, the T-bars having shank parts extending through the tops of the shells, pins extending through another set of slots for connecting the upper ends of the shanks of the T-bars to the slideable bars, and links connecting the upper ends of the shanks to one set of the first named pins for raising and lowering the pointed pins in the shells to release the bags, the T-bars guided by the links and the shells in their reciprocatory movements produced by the slideable bars.

2. In a bag holder, a chute, a pair of slideable bars located on opposite sides of the chute, a handle interconnecting the slideable bars, the bars having cam slots, pins extending through one of the slots for shiftably supporting the bars on the end of the chute for horizontal and vertical movements of the bars, a pair of members connected to the end of the chute below the bars, a pair of T-bars having pointed pins connected to the ends of the cross parts of the T-bars and extending through the members and adapted to engage the ends of the bags, the shanks of the T-bars extending through the said members, pins extending through another set of the slots for connecting the upper ends of the shanks of the T-bars to the slideable bars, links connecting the upper ends of the shanks for directing the raising and lowering movements of the T-bars by the last named slots to release the bags from the pointed pins.

In witness whereof I have hereunto signed my name to this specification.

PAUL W. ERNSBERGER.
